UNITED STATES PATENT OFFICE.

RANDOLPH M. BARRON, OF BEAUMONT, MISSISSIPPI, ASSIGNOR OF ONE-HALF TO
CLAUDE W. WALLACE, OF COLUMBIA, MISSISSIPPI.

VENEER-SPLITTING MACHINE.

Application filed November 29, 1926. Serial No. 151,470.

The present invention relates to a machine for splitting veneer and aims to provide a structure which is highly efficient and reliable in its operation and is capable of doing a great amount of work in a minimum space of time with little effort on the part of a workman.

Another very important object of the invention lies in the provision of a pair of superposed rotary members, one of which is provided with annular cutting tools operable in kerfs in the other roller member.

Another very important object of the invention resides in the provision of superimposed roller members formed in sections, said sections being readily adjustable and capable of easy assembly and disassembly as to shafts on which they are mounted.

A still further very important object of the invention lies in the provision of a machine of this nature which is simple in its construction, inexpensive to manufacture, strong and durable, compact, easy and convenient to work with and otherwise well adapted to the purpose for which it is designed.

With the above and numerous other objects in view, as will appear as the description proceeds, the invention resides in certain novel features of construction, and in the combination and arrangement of parts as will be hereinafter more fully described and claimed.

In the drawing:

Figure 1 is a front elevation of the machine embodying the features of my invention.

Fig. 2 is a side elevation thereof.

Fig. 3 is a top plan view thereof.

Fig. 4 is a longitudinal section through one of the lower roll heads,

Fig. 5 is a longitudinal section through one of the roll heads of the upper roll member.

Referring to the drawing in detail it will be seen that the machine includes a frame formed by two side members 5 and 6 which are connected together with spaced parallel relation by a plurality of cross rods or braces 7 and 8, the former being disposed above the latter in spaced parallelism. It is preferable, as is shown in Fig. 2, to provide two of the brace rods 7 and two of the brace rods 8 although the number of these rods is not of the essence of the invention. A tray

frame 9 is preferably of a substantially U-shaped formation and has its ends pierced by one of the rods 7. Braces 10 incline upwardly and outwardly from one of the brace rods 8 and are attached to the sides of the tray frame as at 11 in any suitable manner.

A cross bar 12 connects the extremities of the tray frame 9 and extends in parallelism with the bight portion thereof. Rods 14 are disposed in spaced parallel relation to one another and are fixed to the bight portion of the frame 9 and to the bar 12 as is clearly illustrated in Figure 3. These rods and the frame 12 incline upwardly and outwardly from the rear side of the main frame. Inclined slots 15 are provided in extensions 16 on the side members 5 and 6 and have bearings 17 slidable therein and operable by screws 18. The shaft 19 of a feed or guide roller 20 is journaled in the bearings 17. Thus the height of this guide roller 20 may be varied as desired.

Vertically disposed slots 21 are provided in the upper portions of the side members 5 and 6 and have bearing blocks 22 and 23 slidably mounted therein, the blocks 22 being disposed above the blocks 23. Springs 24 are disposed in the upper portions of the slots 21 and impinge downwardly against bearing blocks 22 urging them towards bearing blocks 23. These springs 24 also impinge against caps 25 engaged on the upper ends of the side members 5 and 6 by any suitable fastening means 26 and close the upper open ends of the slots 21. Screws 27 are threaded through these caps 25 being locked in different adjusted positions by lock nuts 28. A plate 29 is disposed on the lower end of each screw 27 and engages with the corresponding spring 24 so that the manipulation of the screw gives the proper tension to the spring as may be desired.

Rolls A and B are journaled in the bearings 22 and 23 respectively. The roll A includes a shaft 30 which has its ends journaled through the bearing blocks 22 and on which is disposed a plurality of roll heads H and an idler 31. Each roll head 8 is constructed in accordance with the enlarged detail sectional view shown in Fig. 5. Each head 8 is formed of two sections 32 which include hubs on inner cylindrical portions 33 adapted to be received on the shaft 30, outer flanges 34 and rims 33. The inner

edges of the hub cylinders 33 are held in abutment with each other by a plurality of bolts 36 which pierce openings in the flanges 34 but the inner edges of the rims 35 are spaced from each other to form annular kerfs 37. The roll heads H are held in fixed relation to the shaft 30 by set screws 38 that are threaded through openings in one of the hub cylinders 33.

10 The roll member B includes a shaft 38 which is journaled in bearing blocks 23 and a plurality of roll heads K and an idler 39. Each roll head K is constructed in accordance with the illustration in Fig. 4 and comprises two sections 40 each of which comprises an inner hub cylinder 41 having an outwardly directed annular flange 42 at its inner edge merging into a cylindrical rim 43 disposed concentrically about the hub cylinder in spaced relation thereto. Annular blades 45 are disposed between the flanged ends of the sections 40 and bolts 46 extend through openings in the flanges 42 and through openings in the annular cutting tool 45. These cutting tools 45, of course, project beyond the peripheries of the heads K and are adapted to move in the kerfs 37 as is clearly illustrated in Fig. 1. The sections of the heads may be varied in length 30 as is clearly shown in Fig. 1 and furthermore they consist of three sections as is shown to the right of Fig. 1. The sections of the heads H are preferably provided with diagonal slots 47 so that sawdust which gets into the heads through the kerfs may exit therethrough. A train of gears 48 is disposed between the shafts 30 and 38 to the other side of the side member 5. A pulley 49 is disposed on the shaft 38 at one extremity thereof in order that a belt drive 40 may be associated therewith. Of course, these shafts may be driven in any suitable manner and the example of the drive shown herein is not of the essence of the invention. 45 In using the device the veneer may be temporarily placed on the tray frame 9 and pieces lifted therefrom and guided over the feed roller 20 to engage between whichever heads H and K desired of the roll members 50 A and B.

The heads K are fixed to the shaft 38 by set screws 50 threaded through openings in the hub cylinders 41 as is clearly shown in Fig. 4. It is preferable that the heads H and K have their sections formed by castings although this is not of the essence of the invention.

It is thought that the construction, utility, 60 operation, and advantages of the invention will now be clearly understood without a more detailed description thereof. The present embodiment of the invention has been disclosed in detail merely by way of example since in actual practice, it attains 65 the features of advantage enumerated as de-

sirable in the statement of the invention and the above description. It will be apparent, however, that numerous changes in the details of construction, and in the combination and arrangement of parts may be resorted to without departing from the spirit or scope of the invention as hereinafter claimed or sacrificing any of its advantages.

Having thus described my invention what I claim as new is:

1. A veneer splitting machine including, in combination, a pair of roll members, means urging the roll members towards each other, one of said roll members including a shaft, a pair of roll head sections formed with hub cylinders having outwardly directed annular flanges at adjacent edges merging into cylindrical rims disposed concentrically about the hub cylinders in spaced relation thereto, means fixing one section to the shaft, an annular cutting tool clamped between the sections, and bolts holding the sections and tool together, said other roll member including a shaft, a pair of roll head sections formed with hub cylinders having outwardly directed annular flanges at remote edges merging into cylindrical rims, concentric about and in spaced relation to the hub cylinders and terminating in spaced relation to form kerfs for receiving the cutting tool.

2. A veneer splitting machine including, in combination, a pair of roll members, means urging the roll members towards each other, one of said roll members including a shaft, a pair of roll head sections formed with hub cylinders having outwardly directed annular flanges at adjacent edges merging into cylindrical rims disposed concentrically about the hub cylinders in spaced relation thereto, means fixing one section to the shaft, an annular cutting tool clamped between the sections, and bolts holding the sections and tool together, said other roll member including a shaft, a pair of roll head sections formed with hub cylinders having outwardly directed annular flanges at remote edges merging into cylindrical rims, concentric about and in spaced relation to the hub cylinders and terminating in spaced relation to form kerfs for receiving the cutting tool, the rims of said other roll member being provided with slots to allow the exit of sawdust.

3. A veneer splitting machine including a pair of roll members, means urging the roll members towards each other, one of said roll members including a shaft, a pair of roll head sections formed with hub cylinders having outwardly directed annular flanges at adjacent edges, means fixing one section to the shaft, said flanges merging into cylindrical rims disposed concentrically about the hub cylinders in spaced relation thereto, and an annular cutting tool clamped be-

tween the sections, and bolts holding the sections and tool together, said other roll member being provided with an annular kerf to receive said tool.

5. A veneer splitting machine including a pair of roll members, means urging the roll members towards each other, an annular cutting tool, means for holding the annular cutting tool on one roll member, said other roll member including a shaft, a pair of roll head sections formed with hub cylinders having outwardly directed annular flanges at remote edges merging into cylindrical rims concentric about and in spaced relation to their hub cylinders and terminating in spaced relation to form kerfs for receiving the tool.

5. A veneer splitting machine including a pair of roll members, means urging the roll members towards each other, an annular cutting tool, means for holding the annular cutting tool on one roll member, said other roll member including a shaft, a pair of roll head sections formed with hub cylinders having outwardly directed annular flanges at remote edges merging into cylindrical rims concentric about and in spaced relation to their hub cylinders and terminating in spaced relation to form kerfs for receiving the tool.

ceiving the tool, said rims being provided 20 with openings for allowing the exit of sawdust.

6. A veneer splitting machine including, in combination, a pair of roll members, means urging the roll members towards each other, one of said roll members including a shaft, a pair of roll head sections formed with hub cylinders having outwardly directed annular flanges at adjacent edges merging into cylindrical rims disposed concentrically about the hub cylinders in spaced relation thereto, means fixing one section to the shaft, an annular cutting tool clamped between the sections, and bolts holding the sections and tool together, said other roll member including a shaft, a pair of roll head sections formed with hub cylinders having outwardly directed annular flanges at remote edges merging into cylindrical rims, concentric about and in spaced relation to the hub cylinders and terminating in spaced relation to form kerfs for receiving the cutting tool, a guide roller, means for adjustably supporting the guide roller for feeding veneer between the roll members. 55

In testimony whereof I affix my signature.

RANDOLPH M. BARRON.
